UNITED STATES PATENT OFFICE.

SHERWIN CODY, OF CHICAGO, ILLINOIS.

LOOSE-LEAF COVER AND COPY-HOLDER.

1,328,318.

Specification of Letters Patent. Patented Jan. 20, 1920.

Application filed April 25, 1918. Serial No. 230,642.

To all whom it may concern:

Be it known that I, SHERWIN CODY, a citizen of the United States, residing at the city of Chicago, in the county of Cook and State 5 of Illinois, have invented certain new and useful Improvements in Loose-Leaf Covers and Copy-Holders, of which the following is a specification.

My invention relates to combined loose 10 leaf book covers and copy holders. The object thereof is to provide a cheap and substantial note book cover, which shall be protective of the book when not in use, and which may be used alternatively to provide 15 a substantial support while notes are being taken in the book, or a readily and completely adjustable holder while the notes are being transcribed.

The principles of my invention are illustrated in the drawings, in which—

Figure 1 is an edge view of the device as used for a note book cover;

Fig. 2 is a front elevational view of a portion thereof as used for taking notes or 25 memoranda;

Fig. 3 is a side view showing the same when used as a copy book holder;

Fig. 4 is a bottom view when looked at approximately from the point A;

Fig. 5 shows a portion of one of the 30 covers with the knotted end of the limiting cord passed through the cover slit.

Further describing my invention with reference to the drawings: 1 is a cover member 35 of substantial material, such as book binders board. 2 is a similar cover member of substantially the same character and width, but materially shorter as shown in Fig. 1. The two cover members are attached to each other by a flexible connection 40 3 which should be of stiffened cloth or other durable material. A cord 4, which may be elastic if desired, is passed around the flexible connecting member 3 and forms a loop 45 as shown at 5 in Fig. 1 to hold the latter in place within or upon the said covers. As shown in Figs. 1 and 2, the cord 4 is adapted 50 to support a plurality of leaves or a book, which are suspended therefrom to rest upon the flat face of the cover section 1. A plurality of openings 6 is formed in the free edge of the longer cover member 1, through which is passed a cord, which may also be elastic if preferred, one portion 7 of which will normally lie upon the outer side of said cover 55 member, the ends being attached by a knot

8 and leaving intermediate portions 9. A slot 10 is provided in the lower edge of the shorter cover member 2 within which the connecting portions 9 may be received adjacent to the knot, and through which the latter will be prevented from passing when in such position, as shown in Figs. 3 and 4. The loop formed by the said cord may also be passed around the free edges of the cover 65 to hold them in closed relation as illustrated in Fig. 1.

The use of my device as a protective cover for a note book is shown in Fig. 1. In the same figure the dotted lines indicate the 70 manner in which the two cover members are brought together to expose the book or insert and to provide a substantial support when notes are taken. In Fig. 3 a side view of the device illustrates the use as a copy 75 holder when a considerable slant is desired. The dotted lines indicate the use when a more nearly vertical position is required. It will be noted that the flexible attaching member 3 permits a considerable range of 80 angular position to conform itself to the convenience of the operator.

In order to bring the copy at right angles to the eye when transcribing on the typewriter or the like and the body must be held 85 in a fixed position, the position of the material to be copied may be variously adjusted through varying the length of the shorter cover member, or through varying the divergence of the two cover members by engaging the cord 9 in the slot 10, either at the first knot 8 or at the second knot, so giving the cover members a greater divergence and the copy attached to the longer cover member 1 a slightly different position with reference to the line of vision of the copier. 95

Additional rigidity may be given to the device when used as a copy holder by means of a short cord 11, securely attached to the side of the longer cover member at 12, and slipped into a slot in the side of the shorter cover member at 13; said cord being provided with a series of knots as shown at 14. When intended to be used in combination the knots on cord 11 should be spaced to correspond 100 to the spacing of knots in the lower cord, but it is evident that either may be used separately from the other if desired.

I claim:

1. A book cover and copy holder comprising a plurality of cover members, one of 110 said cover members having a slot extending

inwardly from one edge thereof, a flexible connection between adjacent ends of said members, a book holding cord forming a loop to embrace said flexible connection, a 5 cord attached to the lower edge of one cover member and provided with knots spaced from each other and adapted to engage the slot in the other cover member, and a second cord attached to the side edge of one cover 10 member provided with knots spaced to correspond with the spacing of knots on the last named cord and adapted to engage in a slot in the other cover member.

2. A book cover and copy holder comprising 15 a pair of cover members, a flexible connection between adjacent ends of said members, a book holding cord forming a loop to

embrace said flexible connection, the free edge of one cover member having a pair of spaced openings therein, the free edge of the 20 other member having a slot formed at the corresponding edge and extending inwardly from the edge thereof, and an endless cord passing through the spaced openings in one cover member with the free looped end 25 knotted at spaced intervals and selectively positioned in the other cover member slot whereby the cover members are held in upright inclined formation.

In witness whereof, I have hereunto subscribed my name, this 24th day of April, 1918, at the city of New York, in the county of New York, and State of New York.

SHERWIN CODY.
